EDGE BINDING MACHINE

Rouel R. Campbell, Lynn, Mass., assignor to
United Shoe Machinery Corporation, Borough
of Flemington, N. J., a corporation of New Jersey

Application August 29, 1938, Serial No. 227,407

35 Claims. (Cl. 12—17)

This invention relates to edge-binding machines and is particular concerned with machines adapted to apply a binding which is secured to the work by adhesive, the illustrated machine 5 being utilized for the application of a decorative binding to the edge and adjacent margins of the insoles of shoes.

In certain types of shoes, notably those of the sandal variety, it is customary to apply a decorative binding to conceal the edge of the insole, as in the open shank or between straps and at the open toe. Such decorative bindings have commonly been applied by sewing machines which stitch through the insole and the binding and 10 can only be wrapped around the edge with moderate tension. It is important, however, that the binding shall cling closely to the edge of the work, as this gives the contour which it is intended that the shoe shall have and because, if 15 the binding is not applied tightly, wrinkles are almost inherent and the appearance is inferior. By the use of an adhesive for the attachment of the binding, it is possible to cause the binding to fit very tightly around the edge of the insole and to hold it in that position. The advantage over 20 sewed bindings in this respect is most noticeable in the inwardly curved shank portions of the insole and, with sandal type shoes, the appearance of this area is particularly apparent.

30 In the application of an adhesive binding, the folding of the binding around the edge and adjacent margins of the work requires contact of the binding progressively across the margin so that wrinkles will not be formed and so that 35 the binding will be drawn tightly around the edge. The adhesive for holding the binding on the work may be applied to the binding previously and allowed to dry, or it may be applied freshly just before the binding is directed to the 40 applying machine, or the adhesive may be supplied on a carrier strip. In the latter case, the carrier strip is coated on both faces so that it will adhere both to the binding and to the work and is brought into registration with the binding 45 just as the latter is directed through the applying mechanism.

The general object of the invention is to provide an improved edge-binding machine capable of producing a high quality of work and, at the 50 same time, doing it rapidly enough so that the output of the machine compares very favorably with previously known methods of binding insoles. Novel features of the invention are to be recognized in improved guiding and folding devices to which the operator is enabled to present

an insole in a simple manner, without requiring the exercise of a high degree of skill. The assurance of a tight application of the binding follows from a novel folding construction embodying an abutment having a curved periphery and other members to co-operate with the marginal portions of the binding regardless of variations in the thickness of the work.

5 The control of the width of the margin of the applied binding while maintaining the moving work in close relation to the folder abutment is accomplished in accordance with other features of the invention, by the provision of a novel construction of work-supporting and gripping members, one of which is fixed with relation to the guideway and folder and the other of which is yieldably mounted, both of said members being constructed to urge the work inwardly toward the abutment.

10 The rapid presentation of pieces of work to the machine is greatly facilitated, in accordance with other features of the invention, by a novel arrangement for feeding said work while pressing the binding into contact with the faces of the insole and in an improved device for cutting off 15 the binding which, as illustrated, may be operated while the work is being fed. This novel cutting-off device is associated with a detent-carrying 20 slide operable to grasp the cut end of the binding 25 and bring it forward, ready for application to the next piece of work, such a construction rendering it very easy for the operator to finish the 25 binding of one piece of work and immediately 30 present the next piece of work to the machine.

35 Other features of the invention relate to an improved mechanism for supplying a composite binding strip and adhesive-carrier strip to the applying mechanism. This arrangement, as illustrated, draws both the binding strip and the adhesive-carrier strip from the source of supply 40 in synchronism with the operation of the work-feeding mechanism, without allowing any slack in the material and without setting up any undue tension in the composite strip as it is presented 45 to the applying mechanism.

50 These and other features of the invention will now be described in the following specification, reference being had to the accompanying drawings, in which

55 Fig. 1 is a front elevation of the machine with parts broken away and in section;

Fig. 3 is a plan of the mechanism carried by the cover, a part of which is broken away;

Fig. 4 is a front view of the binding-applying mechanism;

5 Fig. 5 is a back view of the same mechanism;

Fig. 6 is an angular view of the applying mechanism, taken from the back of the machine and with the hammer broken away;

Fig. 7 is a fragmentary view from the same 10 angle, illustrating the action of the hammer in pushing the binding progressively into contact with the work;

Fig. 8 shows the hammer at the end of its downward movement;

15 Fig. 9 is an angular view of the work-receiving end of the machine but with a work gripper broken away to expose the folding and applying mechanism;

20 Fig. 10 is a fragmentary view from a similar angle but showing the upper gripper resting against the lower gripper;

Fig. 11 is a plan view of the binding-applying mechanism, with the upper gripper, the hammer and the cutting-off mechanism broken away;

25 Fig. 12 is a plan view of the reels associated with this guiding and applying mechanism;

Fig. 13 is a front elevation with parts broken away of two of these reels, and

30 Fig. 14 is a fragmentary section on the line XIV of Fig. 12.

The machine is of the bench type and comprises a hollow base 20 having an overhanging arm 22, the left end of which is closed by a removable plate 24. A hollow cover 26, also having a laterally extending arm 28 closed by an end cover 30, is tiltably mounted on the base 20 by pivots 27.

40 In order to support the binding-applying mechanism, the machine is provided with a substantially vertical frame plate 32 which is held in a recess 33 (Fig. 9) on the arm 22 by screws 34 (Fig. 1). Extending horizontally along the front face of this frame plate 32 is a groove 36 (Fig. 9) which receives a slide 38 along the face of which there is provided a guideway for a binding strip 40. The slide is retained in the groove by an overhanging upper flange 37 and an upstanding bottom flange 39 and is normally stationary, it being moved only, as will be later described, first 45 backward and then ahead when the strip is to be severed and the end of the unused portion pushed ahead (to the left as shown in Fig. 1) into work-receiving relation to the applying mechanism. During the operation of the machine in applying 50 the binding to the edge of a piece of work, such as an insole, the binding is held against retrograde movement by a detent 42 pivotally mounted on a stud 44 fastened to the slide. This stud, instead of being at right angles to the face of the 55 slide, is positioned so that it extends inwardly and ahead, with respect to the movement of the binding, at an acute angle to the face of the slide. The lower operative portion of the detent is bent so that in its work-engaging position, it lies substantially parallel to the face of the slide and on its inner face is provided with spurs 46 (Fig. 9) which grip the binding against the face of the slide. This bent end of the pivotally mounted 60 detent 42 moves upwardly and outwardly from the slide during forward movement of the binding strip 40 so as to provide an easily controllable amount of friction against the binding strip. At the same time, being urged downwardly by a spring 48, the detent grips the binding quickly 65 upon attempted retrograde movement thereof.

The tension of this spring 48 may be adjusted by a nut 50 held in place by a lock nut 52. The width of the guideway provided in the front face of the slide 38 is varied for different widths of binding by a block 54 having a horizontal surface 56 to contact with the upper edge of the binding and a vertical surface 58 to hold the binding in against the slide. The block 54 is vertically adjustable on the slide and is held in adjusted position by a screw 60 passing through a vertical slot in the block. The slide is also provided at the bottom with a thin plate 62 which has a horizontal flange abutting the bottom flange 39 of the groove 36, the upper surface 64 of said flange determining the lower limit of the binding guideway on the slide. At the left, this plate has a laterally extending finger 66 which serves, as will be later explained, to guide an incoming end of the binding strip as it is pushed ahead to the applying mechanism.

20 The binding-applying mechanism comprises a folder 70 (Fig. 9) formed at the left end of the frame plate 32 by a U-shaped notch defined by an upper finger 72, a lower finger 74 and an abutment 76 which, in order to reduce friction, 25 may be in the form of a roll. This roll, against which the mid-portion of the binding is pressed as the edge of the work is pushed into the notch of the folder 70 is freely rotatable on a removable pin 77 and the roll may be of resilient material but preferably is constructed of metal in order to make it more durable. It has a grooved periphery diverging outwardly to form a rib at its lower end thereby better to coact with those portions of the insole, such as the shank portion, in which the edge is not normal to the face of the sole. The pressure of the work against the binding strip as supported by this abutment, causes the mid-portion, but frequently not the exact middle of the strip, to adhere to the edge 40 of the work. At the same time, the upper and lower margins of the strip are folded around the margins of the work by the action of the folder as the strip passes through the U-shaped groove provided by the upper and lower fingers 72, 74. 45 A guard plate 78 keeps the strip out of contact with the abutment roller 76 until it is pressed against the left face thereof by the work and this guard plate 78 has a laterally extending portion 80 which lies at the top of the roll and is beveled so as to form substantially a continuation of the curvature of the roll, i. e., laterally and upwardly. It will be noted that the vertical front faces of the fingers 72 and 74 are inclined to the left and forwardly, considering the direction of movement of the work, away from the operator. As a result, the application of the binding to the margins of the insole is progressive across said margins, the binding touching the outer portions of the insole margins before it touches the inner portions. This is valuable in the prevention of wrinkles. If the work is of a thickness such that it practically fills the U-shaped notch, the lower edge of the upper finger 72 and the upper edge of the lower finger 74 will both be effective in this way. If it is of less thickness than the groove, the action of the lower finger 74 will remain the same and the bending of the upper margin around the upper face of the work will be carried out by members to be later described. 50 It should also be noted that bulges 82 and 84 are provided in the folder in order thereby to provide a backing for a natural fullness of the binding strip as it passes from a condition where it is substantially flat to one where it is bent toward 55 60 65 70 75 80 85 90 95 100 105 110 115 120 125 130 135 140 145 150 155 160 165 170 175 180 185 190 195 200 205 210 215 220 the upper and lower margins of the interposed work.

The positioning of the work with respect to this folder 70 is effected by upper and lower work-supporting and gripping members 86 and 88, (Fig. 10) the outer corners of which are beveled at 90 to facilitate the feeding of work such as molded insoles or those thickened at one end by shank reinforcements. The lower member 10 88 is fastened on the frame plate 32 by dowel pins and a screw 92 so that its upper work-supporting face is substantially at the level of the upper face of the lower finger 74 of the folder.

This relation and the fixed relation thereto 15 of the surface 64 at the bottom of the guideway produces a uniform margin of binding on the bottom of the insole and if there are variations in the thicknesses of the different portions of the insole the margin on the upper surface there- 20 of is allowed to vary because it will be covered by a slip sole as the shoe is assembled. This making of a uniform margin of binding upon the lower surface of an insole is especially desirable in shoes in which the outsole is to be 25 attached by means of cement because there are some binding materials to which the sole-attaching cement does not adhere. Accordingly, the uniform margin is made just wide enough so that the binding will be held, while at the same time 30 a large portion of the area to which a sole-attaching cement is normally applied is left uncovered by the binding. The far side of this work-supporting member 88 is separated from the face of the lower finger 74 to provide a 35 groove 94 (Fig. 9) into which the lower margin of the binding strip passes just before it is folded up against the lower face of the work, by its entrance into the U-shaped notch of the folder 70. The gripper members are also made effective 40 to urge the work laterally to press the binding against the abutment roll 76 by providing each of them with a sharp rib and these ribs 95 and 97 (Figs. 4 and 10), located one above the other near the left-end faces of the gripper members 45 86 and 88, are positioned at a slight angle to the path of feeding movement (see the arrow in Fig. 11) so that their tendency is to urge the work inwardly toward the abutment roll. These ribs extend forwardly and inwardly toward the 50 path of feeding movement. One position of an insole S is shown in dot and dash lines in Fig. 11 and the direction of feed is substantially normal to the length of the arm 22, as indicated by the arrow.

The upper gripping member 86 is mounted at 55 the end of the lower arm of a bell-crank lever 96, received in a groove 98 along the upper face of the frame plate 32, and pivotally mounted therein on a stud 100. It is desired to be able 60 to lift this upper work support and gripper 86 for the introduction of a piece of work. To this end, the bell crank 96 has a laterally extending pin 102 over which there engages the hook-shaped end 104 of a rod 106 slideable in 65 the end plate 30 (Fig. 1) and traversing a passageway 103 formed in the arm 23 of the cover 26. Movement of this rod 106 axially to cause it to lift the upper gripper 86 is effected by a treadle rod 110 which, when pushed upwardly, lifts a lever 112 pivoted in the base 20 and having a nose 114 adapted to engage the under side of a bell crank 116 (Figs. 1 and 3) pivoted in the cover 26. This bell crank at its upper end is forked to coact with a stud 118 in another bell crank 120 pivotally mounted in the cover 26 and 70 75

engageable at its laterally bent upper end by two nuts 122 on the rod 106. The action of the treadle rod 110 is effected against the resistance of a spring-pressed pin 124 and clockwise movement of the bell crank 116, as viewed in Fig. 1, is limited by a stop pin 126. The limit of downward movement of the arm of the bell crank 96 which carries the work gripper 86 is determined by an adjustable stop screw 128 (Fig. 6) contacting the frame plate 32. Carried also on this bell crank 96 is a deflector plate 130 having a curved lower end 132 adapted to rest against the partially infolded upper margin of the binding (Fig. 5) thereby to insure the deflection of this upper margin toward the work in the case of unusually thin pieces of work, where the work is enough thinner than the space between the folder fingers so that the upper finger 72 is not fully effective in tilting this margin toward the work.

As the binding is thus applied to the work, a feeding movement is imparted to the bound insole by a mechanism similar to that utilized in folding machines and particularly to a mechanism such as is shown in Letters Patent of the United States No. 1,702,598, granted February 19, 1929, on the application of P. R. Glass. There, as herein, the feeding of the work is accomplished by coacting members which grip the margin of the work and carry it forward. These members are termed a hammer 140 (Fig. 7) and an anvil 142, the latter being detachably mounted on an anvil arm 144 which is clamped to the outer end of a hollow shaft 146 journaled (Fig. 1) in the arm 22 of the frame. A hammer arm 143 is pivoted to the anvil arm at 150 and its lower end is connected to a rod 152 passing through the hollow shaft 146 and adapted to be oscillated axially to move the hammer toward and away from the anvil. Movement of the hammer in gripping the work is effective to complete the application of the upper margin of the binding and is made more so by reason of the fact that the hammer is provided with a tiltable face-plate 154 (Figs. 7 and 8) which has an upstanding semi-circular flange 156 slidable in a correspondingly shaped groove in the under side of the hammer head. The parts are kept in this relation by the transverse pin 158 which passes through a curved slot 160 in this upstanding flange 156. The hammer face-plate 154 presses the binding smoothly against the stock because it is biased to always contact with the marginal portion of the binding first at the corner of the insole S (Fig. 7) and then to bring the binding progressively into contact with the upper surface of the insole inwardly of the margin thereof (Fig. 8). To this end, the hammer is provided with a wire spring 162, the outer end of which enters a recess in the face-plate 154 and the other end of which enters a passage 164 in the hammer arm 143. The upper side of the hammer head is provided with a groove 166 to receive this wire spring and keep it from twisting. The shape of the work-engaging face 60 of the anvil is well shown in Figs. 6 and 9 and from these it will be seen that the anvil is provided with an inwardly and rearwardly directed edge 170. It is desirable that the vertical face at this edge 170 be brought as close as possible 65 to the folder 70 and to this end, the lower arm 74 is cut back, as shown at 172 in Fig. 6.

The face-plate 154 of the hammer has a shape complementary to the shape of the work-engaging face of the anvil. As a result, the upper finger 72 75

of the folder is cut back to permit the hammer to be brought into close relation thereto. The hammer is made somewhat wider than the anvil so that when the work is very thin the hammer 5 will still overlie the whole of the margin of the work and will not be carried outwardly by reason of the pivotal mounting of the hammer arm 148 to a point to the right, as seen in Fig. 8, such that the left edge of the hammer plate 154 might 10 not cover the work. By reason of this construction the rear edge 170 of the anvil and the corresponding edge of the hammer extend diagonally of the margin of the work inwardly and forwardly of the work so that the bite of these members corresponds as nearly as possible to the natural fold of the binding as it is brought gradually 15 into contact with the upper face of the work, thus avoiding any tendency to plait the binding around sharply curved portions, such as at the toe end of the sole S. It will be understood that the bias cut of the binding permits it to stretch 20 to the amount which may be needed so that the binding can be applied smoothly around either convex or concave curves of the work.

25 In many insoles, the edges at the shank portion are not normal to the face of the sole, but are undercut, when, as usual, they are presented right side up and additional assistance in pressing the binding firmly against such undercut 30 edge portions is given by a spring-wire folder 174 having an inclined portion 176 terminating in a vertical end 178. This folder wire 174 is coiled at 180 to cause the vertical end 178 to rub on the vertical face at the back side of the lower finger 35 74 of the folder. As a consequence, when the anvil arm 144 oscillates toward and away from the lower finger 74 of the folder, the inclined portion 176 of the folder wire is given an oscillation transversely of the margin of the work and 40 wipes the binding into firm contact with such undercut edge portions.

Oscillation of the hammer arm 148 to bring the hammer against the work, by oscillation of the rod 152 axially of itself, is effected by a cam 45 182 (Fig. 1) on a driven shaft 184 journaled in the base 20 of the machine. This cam imparts a vibratory movement to a forked lever 186, which movement is transmitted through a link 188 and two arms 190, 192 to the rod 152. The 50 arms 190, 192 are journaled on a common pivot rod 194 and are held yieldably in the relation shown by a spring-pressed plunger 196 within a casing 198 carried by the arm 190 and by a stop screw 199 carried by the other arm 192. By this 55 arrangement, the blow of the hammer is softened. At the same time, in order to compensate for variations in the thickness of the stock, a lighter spring 200 surrounds the rod 152 between the arm 192 and a nut on the end of the rod.

60 Oscillation of the anvil arm 144 to feed the work after the hammer and anvil have been brought into gripping relation with the work is effected by another cam 202 on the driven shaft 184 and by this latter cam movement is imparted 65 to a forked lever 204, the lower end of which is pivoted to an arm on a rockshaft 206. Similarly secured to another arm on the rockshaft is a link 208, the upper end of which is connected to an arm 210 clamped on the hollow shaft 146. By 70 this arrangement, the oscillations imparted by the cam 202 are transmitted to the hollow shaft 146 on which the anvil arm is clamped and the extent of these oscillations is controlled, as in the patented machine, by a finger piece 212 extending outwardly through a slot in the casing. The 75

position of this finger piece is determined by a pin 214, which may be positioned in any one of a series of holes (not shown). On the cam shaft 184 is a driven pulley 220 which may be connected to the shaft at the will of the operator by 5 a clutch mechanism 222 having a trip member 224 pulled to starting position by a treadle rod 226, as more fully shown and described in Letters Patent of the United States No. 2,044,501, granted June 16, 1936, upon the application of P. R. 10 Glass.

After the binding has been applied to nearly all of such portions of the periphery of the work as is desired, the binding may be severed by a knife 230 carried at the outer end of an arm 232. 15 This knife has a diagonal cutting end inclined on a long bevel to minimize any crushing or wrinkling of the binding as the knife becomes dull. The arm 232 is clamped to one end of the transverse stud 100 while integral with the other end 20 of this stud is a depending arm 234 (Fig. 6). The lower end of this arm 234 is slotted to receive a pin 236 passing through a slot 238 in the frame plate 32 and attached to the slide 38. As a consequence, the slide and the knife move 25 simultaneously, the slide 38 (Fig. 9) moving to the right as the knife 230 descends to sever the binding. As the slide moves to the right, it forms a recess 240 (Fig. 4) transversely of the guideway to receive the knife blade. This recess has an extension 242. The recess 240 is formed between a curved edge 244 formed in the frame plate 32 and a complementally curved edge 246 on the slide. The blade-carrier arm has a depending portion 248 against which the 30 blade is clamped by a reinforcing plate 250 (Fig. 9) held on the end of the arm 232 by a screw 252. The far side of the depending portion 248 and the point of the blade 230 pass very close to a ledge 254 at the back of the recess 240 and thus 35 pass behind the binding strip, which is held against crumpling or outward deflection toward the operator by a finger 256 attached to the bell crank 96 carrying the upper gripper 86 and is also held by the overhanging surface 58 (Fig. 9) 40 at the inner side of the block 54. An inclined cut is thus made across the binding strip, which is substantially parallel to the bias threads therein. It will be noted that the binding strip is kept taut during this severing operation because at 45 one side of the knife it is attached to the work still being gripped by the members 86, 88 and at the other side is smoothed out frictionally by the rubbing action of the detent 42, which moves along the surface of the binding as the cut is 50 being made. When, now, the binding has been severed and a piece of work completed, which is removed from the machine, reverse movement is imparted to the slide 38 as the knife is returned 55 to its upward position, shown in Figs. 1, 6 and 9, and during this return movement of the slide, the studs 46 on the detent grip the binding 60 against the slide and cause the cut end to be moved ahead to the left into position where it can be pressed against the abutment 76 by the 65 next piece of work presented to the machine. During this movement, the upper edge of the binding is held against the slide by the surface 58 of the block 54 and the end is pushed into the groove 94 between the folder and the work-supporting member 88 (Fig. 11) by the laterally extending finger 66 carried on the slide.

If, at the beginning of the work or when a new piece of binding is to be threaded through the machine, it is desired to lift the detent 42 70 75

so that it will be out of the way, the slide 38 may be moved still farther to the right than the position shown in Fig. 4 until the detent contacts with a cam finger 260 (Figs. 1 and 2) which is on a block 262, attached to the right end of the frame plate 32 by a screw 264. The knife 230 will then enter the recess extension 242. In order that the slide may not always move far enough to the right to lift the detent, a stop 266 (Fig. 2) is provided which extends downwardly into the groove 36 provided for the slide. When the operator wants to make this cam finger 260 effective, he has only to lift the stop 266 by turning the laterally extending upper end 268 thereof to contact with a curved surface 270 (Fig. 9) formed on the upper edge of the frame plate 32, thereby camming this stop pin 266 upwardly against the tension of a spring plate 272 held in position by the same screw 264 and having its other end 269 (Fig. 11) forked to engage in a groove around said pin.

Actuation of the slide and knife in the above-described manner may be effected by the operator at any desired time, even while the machine is feeding the work, by pulling down on a treadle rod 274 (Fig. 1) to swing a bell-crank lever 276, 278 pivoted on transverse studs 280 in the base of the machine. The treadle rod is attached to the short end 276 which extends to the right from the far end of a yoke portion 279 (Fig. 3) supporting the upstanding end 278. This end 278 carries a pin 282 received in a grooved block 284 fastened on a rod 286 which is slidable in the arm 28 of the cover. This rod 286 is urged to the left (Fig. 1) by a spring 288 received in a recess of the cover arm 28 and acting on a block 290 on said rod within the recess of the arm. A depending pin 291, received in a slot in the lower side of the arm 28, prevents rotation of the rod 286. The arm 278 of the treadle-operated lever is also urged counterclockwise by a spring 292 to contact with a stop pin 294 so that it will always be in position for engagement in the notch of the block 284 when the cover is lifted and returned to position. The outer end of the rod 286, threaded in the block 290, is bent downwardly and then horizontally and is notched, as shown at 296 (Fig. 6), to receive the pin 236 on the slide. This notched end 296 along with the notched end 104 of the rod 106 permits the cover to be lifted around its pivots 27 when it is desired to obtain access to the inside of the machine for lubrication or adjustment. It should be noted, furthermore, that endwise movement of the rod 286 to the right is limited by a stop block 298 threaded in the cover and held in adjusted position by a lock nut. The rod 286 will not ordinarily contact with the stop 298 because of the limitation of the slide movement by the stop pin 266 (Fig. 2). If, however, this stop pin has been lifted, the right end of the rod 286 can only move as far as permitted by the stop block 298, thus permitting the operator to depress the treadle (not shown) attached to the rod 274 firmly without fear of damage to the slide 38 or the knife 230.

The binding, which is to be attached to the work by adhesive, may be freshly coated with a rubber or a thermoplastic adhesive or it may be coated with a thermoplastic adhesive which is activated, as by heat, just as the binding is introduced into the applying machine. Still another arrangement has been proposed in which the adhesive for the attachment of the binding is furnished by a separate carrier strip 300 (Fig. 12),

which strip is coated on both its faces so that it adheres to the binding itself and to the work and thus serves for the attachment of the binding to the work. One of the numerous reasons why an arrangement of this sort is advantageous lies in the fact that many different kinds, colors and widths of binding material are employed in shoemaking. If these are purchased with adhesive coatings, there is a possibility of deterioration of the coatings thereon before the binding is all used. On the other hand, if the bindings strips are uncoated, the manufacturer is required only to provide himself with a sufficient quantity of the adhesive carrier strip 300 to take care of the current production of shoe parts and does not have to maintain a quantity of coated binding which may or may not be completely used during a particular season's run.

The coating employed on this carrier strip 300 is commonly of the pressure-sensitive type, an example of which is found in the so-called surgeon's tape which is in widespread household use. With a carrier strip of this kind, it is essential that a separator strip 302 shall also be employed, which is interleaved between the coils (on a roll 300) of the carrier strip to prevent them from sticking together. Such a separator strip is frequently made of crinoline, similar to coarse cheesecloth, which adheres only lightly to the carrier strip but must be separated therefrom and disposed of before the carrier strip 300 is united with the binding 40. The binding strip 40 and the carrier strip 300 are brought together in alignment with each other before they enter the guideway 56, 64 on the slide 38. This alining of the two strips is accomplished by bringing them together within the flanges of a guide roll 304 freely rotatable about a stud 306 (Fig. 1) which is fastened to an arm 308 bolted at 310 (Figs. 6 and 11) to the anvil arm 144 of the feed mechanism. The purpose of this mounting will be later described. The arm 308 may be adjusted to bring the roll 304 into alignment vertically with the guideway 56, 64. This guide roll 304 has a bottom flange 312 while on the stud 306 there is threaded for adjustment with respect to the flange a normally stationary, inverted, cup-shaped member 314 which with the flange provides an adjustable guide channel adapted to receive bindings of varied widths. The peripheral surface of the cup-shaped member 314 is corrugated and the member is held in adjusted position by a friction detent in the form of a flat plate 316 having a vertical rib entering the corrugations and attached to the end of the arm 308 by a screw 318. This same screw also serves to hold in position a deflector plate 320, the binding-contacting portion of which lies obliquely inclined with respect to the plane of the approaching strip 300 at such an angle, as shown in Fig. 1, as to tilt the lower edge of the carrier strip 300 upwardly (Fig. 11) as it approaches the flange 312 of the guide roll so that the strip will move into engagement with the roll 304 without contacting with the edge of the flange 312. A supply roll 322 (Fig. 12) of the binding strip 40, wound on a flexible core 324, may be supported in any desired manner and is herein shown as freely rotatable about a stud 326 as it rests on a smooth horizontal table 328. The binding strip 40 is directed about a small stud 330 (Figs. 1 and 11) attached to the arm 308 and passes thence to the guide roll 304. By causing the binding 40 to enter the space between the flanges of the guide roll at a point separated 75

from the entering point of the carrier strip 300, a proper registration of the two strips is insured before they are brought into actual contact with each other. The binding is kept from slipping off this stud 384 by a guard 388 secured to the stud by a screw 386 and forming a loop through which the binding must pass, the lower end of the guard being attached to the arm.

The supply roll 330 of the combined separator strip 302 and carrier strip 300 is positioned on a freely rotatable table 332 having a hub 334 supported by ball bearings 336 on a post 338 attached to a pedestal 340. This combined roll 330 is mounted on a core 342 which is centered by a 10 conical portion 335 (Fig. 14) of the hub and is held against the table by an eccentrically mounted locking disk 344 positioned on a stud bolt 346 by which the table 332 is attached to the hub 334.

The crinoline strip 302 is disposed of automatically by being wound about a pick-up reel 350 (Fig. 12), having a slot 352 therein into which an end of the strip 302 is inserted. The pick-up reel 350 is pivoted at the end of an arm 354, itself swingably mounted on a bolt 362 at one end 20 of an arm 356, the other end of which is clamped by a bolt 358 to the post 338. The arm 354 is urged in a counterclockwise direction, as viewed in Fig. 12, by a spring 360 coiled about the bolt 362 and having its ends engaging the respective 25 arms. This spring holds the periphery of the coils of crinoline on the pick-up reel 350 against the coils of the roll 330 regardless of the variations in diameter thereof.

The coils of crinoline on the pick-up reel 350 30 are also held against the coils of the roll 330 by the pull of the carrier strip, acting to assist the spring 360, and the pressure between these rolls can be varied by changing the angular position of the arm 356. For example, clockwise movement of this arm, as viewed in Fig. 12, will cause 35 an increase in pressure between the rolls. It will be understood that the force which winds up the crinoline strip is applied at the point of contact between the two rolls, thus preventing any slack 40 between the point of separation 380 between the strips and the point of contact between the rolls.

The even winding of the crinoline strip on the reel 350 and proper support therefor when of increased diameter are insured by a supporting arm 50 364 (Fig. 13) held by a set screw 366 on the post 338 and having a horizontal portion 368 which is at the left of the table 332. Another arm 370 overlies the two rolls and forces the crinoline strip to wind properly. This arm is pivotally mounted on a pin 372 traversing the upper end 55 374 of the stud 338 thus permitting new rolls 330 to be passed over the arm. A proper horizontal position of the arm above the rolls for any particular width of binding and hence width of carrier and crinoline strips is assured by a stop screw 376 passing through it and resting on a flange 378 above the hub 334.

Inasmuch as there is a tendency for the carrier strip 300 to adhere lightly to the crinoline separator strip 302 at their point of separation 60 380 and since it is desired that the combined binding and carrier strip be delivered to the applying machine without any undue tension which, if present, tends to draw the binding away from the work at concave edges, provision has been 65 made for intermittently drawing small portions of these strips from the supply rolls mechanically in direct proportion to the amount of binding which is being used. It will be understood that the arm 308 oscillates away from and toward the

operator with each feeding and retrograde movement respectively of the anvil 142. When, as viewed in Figs. 11 and 12, the arm 308 is oscillated forwardly, with respect to the direction of feed of the work, or toward the rolls, the binding strip and the carrier strip pass freely around the roll 304 and the stud 384, because at that time the strips are being drawn forward through the guideway 56, 64 by the grip of the hammer and anvil on the work. There will, therefore, be no 10 slackness in the combined strip. On the other hand, during the retrograde movement of the anvil 142 and arm 308 when the work is stationary, owing to the position of the roll 304 with respect to the guideway 56, 64 and the supply rolls 15 322 and 330, the length of binding material and of the carrier strip between the guide and supply rolls is increased by substantially the extent of the feeding movement of the anvil thereby causing an additional length of combined binding 20 and carrier strip just sufficient for the succeeding feeding movement of the machine to be drawn from the respective rolls. It will be recalled that the work is held at that time against retrograde movement by the pressure applied by the upper 25 supporting and gripping member 86, this pressing action being derived through the rod 106, the connected bell cranks and the spring-pressed stud 124 (Fig. 1).

In the operation of the machine, assuming that 30 supply rolls 322 and 330 have been provided and the strips have been threaded into the machine, the upper work gripper 86 having been raised by raising the treadle rod 110, a piece of work, such as an insole S held right-side up, will be pressed 35 against the adhesive binding strip opposite the abutment roll 76 in the folder. Power will then be supplied to the cam shaft 184 by depressing the treadle rod 226, whereupon the hammer 140 will descend to grip the work against the anvil 142 and will draw the work and the binding through the machine during the first half 40 of one cycle of its operation. During this operation, the lengths of binding and carrier strips drawn from their respective rolls during the preceding retrograde movement of the anvil are united in passing the roll 304, and the combined binding and strip after passing under the detent 42 and through the guideway 56, 64 45 will be attached at a mid portion of the strip 50 to the edge of the insole as the latter is pressed against the binding supported by the abutment roll 76. At the same time, the binding, being drawn between the fingers 72 and 74 of the folder, will be turned over and under the margins of the 55 work and finally will be forced into firm contact with those margins by the action of the hammer and anvil.

During the retrograde movement of the hammer and anvil, the work will be held by the cooperating grippers 86 and 88 and by reason of the action of the retrograde movement of the guide roll 304 in increasing the total distance between the point of attachment of the combined strip to the then stationary work and the rolls, lengths 60 of carrier strip and of binding strip will be drawn from the respective rolls, these lengths being substantially equal to the length of feeding movement imparted to the work by the machine. It will be recalled that the oscillating spring wire 65 176 is effective to cause the binding to adhere to undercut portions, such as at the shank portion of an insole, and that the deflector plate 130, 132 (Fig. 6) is effective to cause the binding to overlie the upper margin of the sole in the case of 70 75

relatively thin work. As the binding of the insole is completed (it being understood that some insoles are bound along portions of their periphery while other insoles are bound completely), the knife 230 will be operated by depressing the treadle rod 274. This may be done while the feeding of the work continues, thus allowing the binding operation to be immediately completed and the insole removed from the machine. As the knife descends to sever the binding, the slide 38 is moved to the right, allowing the detent 42 to get a new grip on the binding at a point removed from the folding and attaching apparatus. As soon as the operator removes his foot 15 and allows the treadle rod 274 to rise under the action of the springs 288 and 292, the slide will move to the left, carrying with it a projecting portion of the binding which is guided into the slot 94 by the action of the projecting finger 66 and is thereby positioned in front of the abutment roll 76 ready for the presentation of another piece of work.

Having described my invention, what I claim as new and desire to secure by Letters Patent of the United States is:

1. In an edge-binding machine, binding-applying mechanism, and binding-guiding mechanism comprising a detent to prevent backward movement of the binding strip, said detent being pivoted about an axis extending inwardly and ahead with respect to the normal movement of the binding through said guide.

2. In an edge-binding machine, binding-applying mechanism, a binding guideway for directing the binding toward the applying mechanism, a stud extending inwardly and ahead with respect to the normal movement of the binding through said guideway, a detent for the binding pivotally mounted on said stud, and a spring coiled around 40 the stud urging the detent into contact with the binding.

3. In an edge-binding machine, binding-applying mechanism, a guideway for directing the binding to the applying mechanism, a slide associated with and forming a part of said guideway, a detent on said slide, operator-controlled mechanism for moving said slide backward with the detent sliding over the binding and ahead with the detent grasping the binding to present a portion thereof to the applying mechanism, and a cam for lifting the detent upon movement in a backward direction.

4. In an edge-binding machine, binding-applying mechanism, a guideway for directing the binding to the applying mechanism, a slide associated with and forming a part of said guideway, a detent on said slide, operator-controlled mechanism for moving said slide backward with the detent sliding over the binding and ahead with the detent grasping the binding to present a portion thereof to the applying mechanism, a displaceable stop for limiting the movement of said slide, and a cam beyond said stop for lifting said detent.

5. In an edge-binding machine, binding-applying mechanism, a guideway for directing the binding thereto, a knife-blade movable transversely of said guideway, a slide forming part of the guideway, and means for moving said slide backward to provide a recess between normally adjacent parts of the guideway to receive the knife-blade as it severs the binding therein.

6. In an edge-binding machine, a frame, binding-applying mechanism, supporting means providing a guideway and a groove for directing

the binding to said mechanism, said guideway comprising a slide mounted for movement in said frame, and a finger on said slide overlying one margin of the binding and extending lengthwise ahead beyond the end of the slide into said 5 groove.

7. In an edge-binding machine, binding-applying mechanism, a guideway directing the binding to said mechanism, a knife mounted for arcuate movement across said guideway, a slide forming 10 part of the guideway, and means for moving said slide back along the guideway to provide a recess for the passage of the knife and for moving the knife along the recess from behind the binding thereby to sever the binding. 15

8. In an edge-binding machine, binding-applying mechanism, a guideway directing the binding to said mechanism, said mechanism having a curved wall the surface of which if extended would intersect the guideway, a knife 20 mounted for arcuate movement in close relation to said wall, a slide having a curved end abutting said wall, and means for moving said slide to provide a curved recess for the passage of the knife and for moving the knife to sever the bind- 25 ing.

9. In an edge-binding machine, binding-applying mechanism, an open-sided guideway for directing the binding to said mechanism, a knife-blade mounted for movement transversely 30 of the guideway to sever the binding, and a finger mounted on the outer side of the binding strip to support the binding against deflection during the cutting action of the knife.

10. In an edge-binding machine, binding-applying mechanism, a guideway comprising a spring detent for holding taut a portion of the binding extending between that portion which has already been applied and a source of supply for the binding, a knife-blade, and means supporting said knife-blade for movement in an arcuate path from edge to edge of the binding to sever it while thus held taut. 40

11. In a machine for applying edge binding by means of adhesive, a folder having fingers overlying and underlying the margins of the work, and a hammer-and-anvil mechanism having rear edge portions which are inclined inwardly toward the edge of the work and forwardly with respect to the direction of feeding movement of 50 the work, said folder fingers having edges adjacent to the work both along forward and rear faces which are inclined forwardly and inwardly toward the edge of the work, one set of said edges being substantially parallel to the edges 55 of the hammer and anvil.

12. In a machine for applying edge binding by means of adhesive, a folder mechanism for wrapping the binding around the edge of the work as it is fed through said mechanism, and a work-supporting member positioned rearwardly with respect to the direction of feeding movement of the work and laterally of said folder mechanism and spaced from said folder mechanism to provide a slot for receiving one margin of the binding as it approaches the folder mechanism. 60

13. In an edge-binding machine, a guideway for a binding strip, and means for supporting a piece of work in a predetermined relation to said guideway comprising work-gripping blocks one of which is yieldable away from the other thereby to compensate for varying thicknesses of the work, one of said blocks having a guiding rib extending forwardly with respect to the direction 70 75

of feeding movement of the work and inwardly toward the edge of the work near the point of application of the binding.

14. In a machine for applying edge-binding by means of adhesive, a guideway for the binding strip, applying mechanism comprising an abutment against which the work may press a mid-portion of the binding strip, work-feeding mechanism located forwardly of the abutment with respect to the direction of feeding movement of the work, and means for supporting and gripping the unbound work piece prior to its engagement with the abutment.

15. In a machine for applying edge binding by means of adhesive, a guideway for the binding strip, applying mechanism comprising an abutment against which the work may press a mid-portion of the binding strip, mechanism for intermittently feeding the work and pressing the binding strip against the faces of the work adjacent to the margin thereof, said work feeding mechanism being located forwardly of the abutment with respect to the direction of said movement of the work, and work supporting members located adjacent to said abutment.

16. In a machine for applying edge binding by means of adhesive, a guideway for the binding strip, applying mechanism comprising an abutment against which the work may press a mid-portion of the binding strip, mechanism for feeding the work along a path located forwardly of the abutment with respect to the direction of feeding movement of the work, and work-supporting members located adjacent to the abutment and engaging the body of the work, one of said members having a rib extending forwardly with respect to the direction of feeding movement of the work and toward the edge of the work and coacting with the work to guide it against the abutment.

17. In an edge-binding machine, binding-applying mechanism comprising spaced folder fingers for folding the binding partially about the margin of the work, means for intermittently feeding the work and pressing the binding against the faces thereof adjacent to the margin of the work, gripper members arranged to hold the work between feeding movements of said feeding means, and a deflector plate carried by one of said gripping members to bend a margin of the binding toward the work, said deflector plate being located between said folder fingers and said feeding means.

18. In a machine for applying edge binding by means of adhesive, mechanism for wrapping the binding around the edge of the work, means for pressing the binding into contact with the face of the work comprising a pivoted hammer having a face plate tiltably mounted thereon, and means to bias said face plate downwardly at its inner edge thereby to contact first with the binding adjacent to the edge of the work.

19. In an edge-binding applying machine, a hammer for pressing the binding into contact with the face of the work adjacent to the edge thereof, said means including a movable face plate and means biasing the face plate downwardly at its inner edge thereby to contact first with the binding adjacent to the edge of the work.

20. In a binding-applying machine, a hammer having a grooved head, a face plate rockably mounted on said hammer, and a wire spring extending through the groove of the head and arranged to lift the outer edge of the face plate.

21. In a machine for applying edge binding by means of adhesive, binding-applying mechanism, and means for pressing the binding into firm engagement with the faces of the work comprising a coacting hammer and anvil, said hammer being tiltably mounted and provided with a face plate the shape of which is complementary to the shape of the anvil but which is wider than the anvil in a direction transverse to the edge of the work. 10

22. In a machine for applying binding to the edge of a piece of work by means of adhesive, binding-applying mechanism comprising a folder for wrapping the binding around the work, said folder having fingers overlapping the work, and a hammer and anvil for pressing the binding against the work and feeding the work, said hammer and anvil having projections extending rearwardly with respect to the direction of feeding movement of the work and said folder fingers being cut away to receive said projections. 15

23. In a machine for applying binding to the edge of an insole by means of adhesive, binding-applying mechanism, work-feeding mechanism forward of the applying mechanism with respect to the direction of feeding movement of the work, and a resilient member inclined upwardly and outwardly from the work, said resilient member being attached to said feeding mechanism and constructed and arranged to press the binding against beveled portions of the edge of the work. 25

24. In a machine for applying edge binding by means of adhesive, folder mechanism for wrapping the binding around the edge of the work, oscillatory feeding mechanism for moving the work forward, and a resilient member attached to said feeding mechanism arranged to rub along the forward face of the applying mechanism considered with respect to the direction of feeding movement of the work to translate the movements of the feeding mechanism into lateral movements of the member, said resilient member having a portion inclined upwardly and outwardly from the work and arranged to rub the binding into contact with beveled edge portions of the work. 40

25. In a binding-applying machine, a base, an operator-controlled device mounted in said base, a cover separable from said base, an intermittently operated tool on said base, and a rod in the cover for connecting the tool to said operator-controlled mechanism provided with notched ends for association with the latter mechanism and the tool respectively whereby the cover may be readily removed and as readily replaced thereby restoring said connection. 50

26. In a binding-applying machine, a base, an operator-controlled device mounted in said base, a cover separable from said base, an intermittently operated tool on said base, a rod in the cover for connecting the tool to said operator-controlled mechanism provided with notched ends for association with the latter mechanism and the tool respectively, and means for biasing said operator-controlled mechanism and said connection to predetermined positions thereby to facilitate reconnection when the cover is replaced. 60

27. In a binding-strip applying machine, applying mechanism, an oscillatory work-feeding member, a flanged guide roll for the strip movable with said feed member, and a strip deflector associated with said guide roll. 70

28. In a binding-strip applying machine, ap- 75

- plying mechanism, an oscillatory work-feeding member, a flanged guide roll for the strip movable with said feed member, and a strip deflector associated with said guide roll, said strip deflector having a binding contacting portion which lies obliquely with respect to the plane of the approaching strip to tilt the lower edge thereof upwardly as it approaches the flange of the guide roll. 5
- 10 29. In a binding-applying machine, applying mechanism, oscillatory work-feeding members, a guide roll for the binding, and an associated strip-aligning roll, both of said rolls being movable with said feed members. 10
- 15 30. In a machine for applying edge-binding by means of adhesive, applying mechanism, oscillatory work-feeding members, means for supplying a binding strip, means for supplying an adhesive strip, and a guide roll for combining said strips and directing them to the applying mechanism, said roll being mounted for movement with said feed members. 15
- 20 31. In a binding-strip applying machine, applying mechanism, holders for a binding strip supply and an adhesive strip supply, a strip-aligning member to which said strips are led from their respective holders, and a guide for one strip and associated with said member in such relation thereto as to cause said strips to approach said member at a substantial angle to each other. 20
- 25 32. In a binding-strip applying machine, applying mechanism, holders for a binding strip supply and an adhesively coated strip supply, a flanged member at which said binding and adhesively coated strips are united and from which said strips are led to said applying mechanism, and a guide associated with said member adapted to direct one of said strips into engagement with said member before said strips engage each other. 30
- 30 33. In a binding-strip applying machine, ap- 35
- plying mechanism mounted for feeding movement in one direction and having alternately therewith an opposite retrograde movement, holders for a binding strip supply and an adhesively coated strip supply, a strip-aligning device to which said strips are led from their respective holders, and means for intermittently operating said device to draw lengths of said strips from their respective sources of supply sufficient for a feeding movement of the work. 10
- 35 34. In a binding-strip applying machine, applying mechanism mounted for feeding movement in one direction and having alternately therewith an opposite retrograde movement, holders for a binding strip supply and an adhesively coated strip supply, a strip-aligning member to which said strips are led from their respective holders, and connections operated by said applying mechanism for moving said member transversely of said strips during the retrograde movement of said mechanism to draw lengths of said strips from their sources of supply and for moving said member during the feeding movement of said applying mechanism to unite the aligned strips. 25
- 40 35. In a binding-strip applying machine, means for pressing a binding strip against a work-piece, means for imparting a feeding movement to said pressing means in one direction and alternately therewith an opposite retrograde movement, a binding strip guide adapted to engage the strip between its source of supply and said pressing means, and mechanism adapted to utilize the retrograde movement of said pressing means for moving said guide transversely of said strip to such an extent as to increase the distance between the point of attachment of the strip to the work and the strip supply by an amount substantially equal to the length of feeding movement of said pressing means. 40

ROUEL R. CAMPBELL.
